A. BEMENT

AIR MOISTENER

Filed Jan. 21, 1921

UNITED STATES PATENT OFFICE.

ALBURTO BEMENT, OF CHICAGO, ILLINOIS.

AIR MOISTENER.

Application filed January 21, 1921. Serial No. 438,869.

To all whom it may concern:

Be it known that I, ALBURTO BEMENT, citizen of the United States, residing at Chicago, Illinois, have invented certain new and useful Improvements in an Air Moistener; and I do hereby declare the following to be a full, clear, and exact description of the invention, such as will enable others skilled in the art to which it appertains to make and use the same.

My invention relates to humidifying devices, its general objects being those of providing a simple, inexpensive and effective device suitable for utilizing steam in moistening air. For this purpose, my invention aims to provide a humidifying device which can readily be attached to the piping of an ordinary steam heating installation, which will be silent in operation, which will not ordinarily allow any of the escaped steam to condense on its surface, and which will catch the drip from such condensed steam in case it should be used under circumstances permitting of such condensation. Furthermore, my invention aims to provide a device of this kind with a unitary mounting including a conveniently disposed valve for controlling the operation of the moistening device. It also aims to provide an air moistener which can be designed to operate effectively with widely varying pressures of steam, including the exceedingly low pressure used in the so-called vapor heating systems. Still further and more detailed objects will appear from the following specification and from the accompanying drawings in which—

Fig. 1 is an elevation of one end of a radiator, showing the steam supply pipe as carrying an air moistener embodying my invention.

Fig. 2 is an enlarged central and vertical section through the air moistener of Fig. 1 along the line 2—2.

Fig. 3 is a horizontal section taken through Fig. 2 along the correspondingly numbered line of that figure.

Fig. 4 is a fragmentary central and vertical section through a more simple form of my moistener, namely one employing only loose asbestos for the silencing.

Fig. 5 is a similar section through an embodiment in which the silencing is effected by loose asbestos and sheet asbestos both

disposed between two concentric cylinders 55 of wire gauze.

Fig. 6 is a fragmentary enlargement of the inner portion of Fig. 3, showing the manner in which the portions of steam are subdivided while passing through the silencing walls.

Generally speaking, I accomplish some purposes of my invention by causing the steam to issue through a wall which affords a large number of fine and winding passages 65 in which the steam is gradually expanded while passing from an inner steam chamber to the outer air, and by maintaining the temperature of the steam during its said expansion; also, by providing simple and 70 good-looking means for maintaining this wall in operative position and for automatically draining off any moisture which may be carried by the entering steam into the steam chamber. This resulting drain or 75 drip I desirably feed back into the steam pipe, and for that purpose I am here showing the moistener of my invention as including a tubular stem 1 threaded at its lower end for attachment through a suitable pipe connection 2 to feed pipe 3 of a low pressure radiator 17. The riser 1 has fast upon it an upper head 11 with a relatively small bore or port 4 through which steam can be admitted to the interior of the 80 percolating or silencing wall which forms one of the main operative portions of my moistener. This wall 8 is desirably composed of a material having a quite low specific heat, such as asbestos, and desirably 85 is in the form of a downwardly open elongated thimble mounted on the said head 11, so that the steam passing through this port will enter the interior of the thimble. Consequently, the elongated chamber 5 which 90 forms the interior of the thimble serves as a distributing chamber for permitting the steam to distribute itself throughout the inner surface of the wall 8.

To maintain this thimble-shaped wall in 100 its proper shape and to preserve the desired uniformity of distribution of the packing material, I desirably pack the asbestos 8 between two perforated walls each of which also is substantially thimble-shaped and 105 each of which walls desirably has its entire side portions formed of a foraminous material such as a wire gauze. For this pur-

pose, I am here showing an inner reinforcing thimble comprising a cylinder 6 of wire gauze brazed at its lower end to the cap 11 and having its upper end 9 also made 5 of wire gauze, so that the steam in the chamber 5 may readily distribute itself through the openings in this entire inner wall member. The gauze portions 6 and 9 may be of relatively light metal, but I de- 10 sirable employ a heavier gauze 7 for the cylindrical side portion of the reinforcing wall which surrounds the packing 8, thereby securing adequate stiffness for preventing 15 mechanical injury to my appliance. This perforate cylinder 7 is here shown as soldered or brazed both to the head 11 of the riser and to an upper head 10, which latter head cooperates with the cylinder 7 in affording an outer reinforcing thimble 20 for the asbestos packing.

Thus arranged, the meshes of the inner gauze portions 6 and 9 initially subdivide the steam into a large number of minute streams, and in winding their way through the pack- 25 ing 8 to the larger gauze tube 7 which has a correspondingly greater total area of apertures, these streams will be still more sub- divided before they reach the openings in this gauze cylinder 7. By thus expanding 30 the steam during its passage through the interstices of the packing, I can readily re- duce its pressure without lowering its tem- perature sufficiently to cause any condensa- 35 tion within the passages, and hence obtain an entirely silent action. To aid in main- taining the requisite temperature, I prefer- ably employ for the packing a material hav- 40 ing a low specific heat, such as asbestos in the form of loosely packed fibres. Further- more, since the cylindrical screen 7 is made of a good heat conducting material and is directly secured at its lower end to the head 11 which is heated by the incoming steam, this screen is also kept continuously heated, 45 so that this heat conduction aids in keeping the packing sufficiently hot to avoid any con- densation of the steam while passing through the packing. By carefully select- 50 ing the material for the packing and uni- formly distributing this to avoid any unduly large passages through the same, and by proportioning the thickness and compactness of this packing to the available steam pres- 55 sure, I can therefore cause the emitted steam to issue without any noise whatever and in a sufficiently dry form to avoid having it condense on the surface of the outer screen.

However, practical difficulties may be met in selecting asbestos of the desired uni- 60 formity, in packing this evenly, and in main- taining this uniformity of packing in spite of the jarring to which such an appliance may be subjected during the rough handling of the packages in which such goods are 65 shipped. I therefore desirably employ part

of the packing or percolating material in the form of a previously fabricated sheet having a definitely determined distribution of the material and having quite fine passages winding through the same, such as a sheet 70 of asbestos. For example, Fig. 2 shows such a relatively thin auxiliary asbestos sheet 12 wrapped outside the gauze cylinder 7 and held in position by an outer perforated 75 sleeve 13, the latter being desirably also of wire gauze and desirably being nickelized or otherwise plated to afford a handsome finish for the moistener.

To control the operation of the moistener, I desirably provide suitable means for gov- 80 erning the admission of steam through the port 4, such as a valve 14 controlled by a readily accessible handle 15. This valve 14 is desirably mounted within the stem 1, so that the latter serves as a mounting both for 85 the control valve and for the moistener proper, and the valve is preferably so positioned that any condensation occurring within the moistener after the steam supply is shut off will drain into the supply pipe. 90

By suitably proportioning the thickness of the expansion-permitting packing or packings in relation to both the material used for this purpose and the available steam pres- 95 sure, I can readily construct moisteners as above described for use with any desired pressure of steam; and since the construc- 100 tion of my moistener affords a relatively direct outlet for the steam, I can employ it effectively even with so-called vapor heating systems working under heads of as low as two ounces. In practice, I have found that a properly proportioned moistener constructed along these lines will be free from any outer condensation or drip under ordi- 105 nary conditions of operation. However, cir- 110 cumstances might arise where some con- densation might occur initially if steam is admitted to a moistener while the metal parts of the latter are quite cold. I am there- 115 fore also showing the riser 1 as carrying a drip cup 16 surrounding the base of the steam-pervious part of my moistener, so that this metal drip cup will catch any con- 120 densed moisture and will evaporate the lat- 125 ter as soon as the metal parts of the appli- 130 ance are heated up. I am also showing my appliance as used in a vertical position with the thimble-shaped portions opened down- 135 wardly, so that any moisture carried upward with the entering steam or condensed within the chamber 5 will drain by gravity through the port 4 into the steam supply pipe.

However, I do not wish to be limited to the use of my appliance in this particular position, nor to the various details of construction and arrangement as above disclosed. Neither do I wish to be limited to its use in connection with household heating 130

appliances, since it might be employed with equal advantage for moistening air in textile mills, bakeries or other industrial establishments. Obviously, various additions, omissions or other changes might be made without departing from the spirit of my invention or from the appended claims. For example, Fig. 4 shows a central and vertical section through the upper portion of a moistener in which the entire expansion of the steam is effected by a loose asbestos packing disposed between two concentric thimbles, each of which has its upper end as well as its side portions made of wire gauze, such a simplified form being ample for factory work where it is not necessary to have the finish afforded by the auxiliary outer casing and the cast head of the embodiment shown in Fig. 2. Likewise, Fig. 5 shows a similar section through an embodiment in which the outer layer 12 of sheet asbestos is also disposed inside the wire gauze cylinder 7, so that the loose asbestos is packed between this sheet and the inner gauze thimble.

With each of the illustrated embodiments it will be evident that the surface of the outer metal screen will be much greater than that of the inner screen, thereby permitting the total area of apertures in the outer screen to be correspondingly larger than those of the inner screen. Consequently, the steam must expand while passing from the said smaller aperture area to the larger aperture area, and by interposing a suitable material for causing this expansion to be effected quite gradually and subdivisionally, I obtain the desired entirely silent action.

I claim as my invention:

1. In an air moistener, a substantially thimble-shaped body of loose asbestos packing, means for admitting steam to the bore thereof, and retaining means for maintaining the packing in its thimble-shaped form while permitting the percolating of steam through the side portions thereof; the said retaining means including a tube of sheet asbestos and a foraminous metal tube both disposed outside of the said packing.

2. In an air moistener, a pair of concentric and substantially thimble-shaped metal members having foraminous side portions, means for admitting steam to the bore of the inner member, a steam-pervious packing disposed between the two members, a metal moistener base supporting both metal members and in heat-conveying contact therewith, and means for admitting steam to the inner of the said members through the base while subjecting the base to the heat of a relatively larger amount of steam.

3. In an air moistener, steam-pervious silencing means comprising an inner tube of loosely packed asbestos fibre and an outer and thinner walled tube of sheet asbestos.

4. In an air moistener, steam-pervious si-

lencing means comprising an inner tube of loosely packed asbestos fibre and an outer and thinner walled tube of sheet asbestos, and non-porous closures for both ends of the said tubes.

5. In an air moistener, a hollow member having a lower inlet for steam and a closed upper end and having a porous wall affording a plurality of minute and tortuous outlet passages of gradually increasing total cross-sectional area, a drip cup surrounding the lower end of the said wall, and means surrounding the said inlet and in heat-conducting relation to both the inlet and the drip-cup for heating both thereof.

6. An air moistener comprising a hollow member closed at its top and having a lower inlet for steam and having a porous wall affording a plurality of minute and tortuous outlet passages leading radially of the said member to the outer air, a valve controlling the inlet, and a unitary mounting for the valve and the said hollow member; the said mounting comprising a member having an inlet at its bottom and having a steam supply chamber surrounding the valve and connected to the said inlet by a tube of considerably smaller bore than the steam supply chamber, both the said tube and the said valve having wall portions exposed within the steam supply chamber so as to subject the said tube and valve to the heat of the steam within the said chamber.

7. An air moistener comprising a riser pipe connected to a supply of dry steam, a closure for the said upper end including a smaller pipe extending downwardly into the riser pipe and opening into the latter near its lower end, a valve controlling the said opening, a laterally perforate tube into which the upper end of the smaller pipe opens, and a steam-pervious packing laterally surrounding the said tube.

8. An air moistener comprising a vertical riser pipe connected to a supply of dry steam and having an upper end closure equipped with a perforation, a pair of foraminous and vertical cylinders mounted on the said closure coaxial with the perforation and in heat-conducting relation to the closure, and a packing of steam-pervious material filling the space between the cylinders and arranged for affording a plurality of fine and tortuous passages from the bore of the inner cylinder to the outer air, the said packing comprising a relatively thick hollow tube of loose material and a thin tube of sheet material housing the said hollow tube.

9. An air moistener comprising a hollow member closed at its top and having a lower inlet for steam and having a porous wall affording a plurality of minute and tortuous outlet passages leading radially of the said member to the outer air, a valve controlling the inlet, and a unitary mounting for the

valve and the said hollow member; the said mounting comprising a member having an inlet at its bottom and having a steam supply chamber surrounding the valve and connected to the said inlet by a tube of considerably smaller bore than the steam supply chamber, both the said tube and the said valve having wall portions exposed within the steam supply chamber so as to subject 10 the said tube and valve to the heat of the

steam within the said chamber, the said hollow member being seated directly upon the top of the steam supply chamber so as to subject the lower end of the hollow member to the heat conducted through the said top 15 from the steam in the steam supply chamber.

Signed at Chicago, Illinois, January 18, 1921.

ALBURTO BEMENT.
